ATTORNEY'S

UNITED STATES PATENT OFFICE

125,668

DESIGN FOR A DRESS ENSEMBLE

Anna Naubert, Chicago, Ill.

Application December 20, 1940, Serial No. 97,475

Term of patent 3½ years

To all whom it may concern:

Be it known that I, Anna Naubert, citizen of the United States, residing at 7728 Marshfield Avenue, Chicago, in the county of Cook and State of Illinois, have invented a new, original, and ornamental Design for a Dress Ensemble, of which the following is a specification, reference being had to the accompanying drawing, forming part thereof.

The characteristic feature of my design resides in the combination on the ensemble disclosed of the specific jacket member having tasselled appliques arranged in the front quarters as shown.

I claim:

The ornamental design for a dress ensemble, substantially as shown and described.

ANNA NAUBERT.
